UNITED STATES PATENT OFFICE

117,558

DESIGN FOR A BAG FOR TOILET ARTICLES

Charles Doppelt, Chicago, Ill.

Application August 1, 1938, Serial No. 79,004

Term of patent 7 years

To all whom it may concern:

Be it known that I, Charles Doppelt, a citizen of the United States, residing at Chicago, and the county of Cook and State of Illinois, have invented a new, original, and ornamental Design for Bags for Toilet Articles, of which the following is a specification, reference being had to the accompanying drawing, forming part thereof.

Figure 1 is a perspective view of a bag for toilet articles showing my new design in closed position.

Figure 2 is a fragmentary perspective view of one end of the bag in open position with the remainder of the bag and portions of the handle broken away for convenience of illustration.

I claim:

The ornamental design for a bag for toilet articles, as shown and described.

CHARLES DOPPELT.
